UNITED STATES PATENT OFFICE.

EDWARD J. BROOKS, OF EAST ORANGE, NEW JERSEY, ASSIGNOR TO
E. J. BROOKS & CO., OF NEW YORK, N. Y.

BAGGAGE-SEAL.

SPECIFICATION forming part of Letters Patent No. 314,164, dated March 17, 1885.

Application filed January 5, 1885. (No model.)

To all whom it may concern:

Be it known that I, EDWARD J. BROOKS, a citizen of the United States, residing at East Orange, in the State of New Jersey, have invented a new and useful Improvement in Seals, ("T,") of which the following is a specification.

This invention, in common with several seal inventions heretofore patented by me, relates to improvements in the method of and means for sealing, fastening, or securely uniting the ends of flexible shackles of "tin" (tin-plate.)

The present invention is more particularly additional to my improvement in seals ("XX") patented May 6, 1884, (United States Letters Patent No. 298,168;) and it consists in an improved seal composed of a hard and brittle disk of peculiar construction and a peculiarly-punched tin shackle, simple punching by means of ordinary plier-punches sufficing to fasten the seal at the sealing operation and to unite the parts preliminarily to facilitate carrying and applying them, while the respective shackle ends are held in the seal-disk independently of each other and in a uniform and secure manner, and the seal-disk is thin, of light weight, and peculiarly convenient to handle, as compared with other hard and brittle seal parts.

A sheet of drawings accompanies this specification as part thereof.

Figure 1 of these drawings is an elevation of a shackle and seal disk as united preliminarily. Fig. 2 is an edge view of the same as applied to a pair of car-door staples by way of example, illustrating the fastening operation. Fig. 3 is an edge view of the fastened seal. Figs. 1^x, 2^x, and 3^x are magnified sectional views corresponding with Figs. 1, 2, and 3, respectively; and Fig. 3^x is a magnified face view of the fastened seal.

Like letters of reference indicate the same parts in the several figures.

This improved seal is composed of a flexible shackle, A, of tin, (tin-plate,) and a hard and brittle seal-disk, B, preferably of "Babbitt metal." The shackle before it is united with the seal-disk is an ordinary rectangular strip sheared from the commercial sheet of the metal, but is preferably colored and provided with printed distinguishing-marks m (either or

both) on one side, as indicated in Fig. 3^x, to render counterfeiting difficult or impossible. The seal-disk is cast in suitable molds, and may be provided therein with permanent distinguishing-marks, or may subsequently be colored, so as to distinguish the seal-disks appropriated to particular roads or users, as set forth in my specification forming part of said patent of May 6, 1884. Said seal-disk is constructed of about the size and shape of a small 60 pressed seal-disk of lead, but with smooth rounded edges, and so as to confine the extremities of the shackle within it, whereby it is rendered easy to handle in applying it and inspecting the seal. Handling it, and its manufacture as well, are further facilitated by its adaptation to be used as it is picked up, with either side thereof as its face, while it serves none the less when united preliminarily with the shackle, as shown in Figs. 1 and 2, to insure the exposure of the printed face of the latter. To these ends, and with reference to the peculiar punching of the shackle aforesaid, the seal-disk has a threading-hole, h, Figs. 1^x, 2^x, 3^x, extending inward parallel to its sides, and nearly but not quite through the disk. Below this is a solid bottom, b, against which the extremities of the inserted shackle ends abut, as shown at the left in Fig. 2^x. Perpendicular to the sides of the seal-disk a pair of central 80 punching-apertures, a' a'', extend inward from its respective sides. With one end of the shackle inserted for preliminarily uniting the parts, it is punched through the aperture a'', for example, its back being toward this aperture, and a strong retaining-burr, b', is formed within the other aperture, a', the walls of the latter co-operating with the punch to set the metal of the burr perpendicular to the face of the shackle. This may preferably be done at 85 the factory, and the seals be shipped in the state represented by Figs. 1, 1^x. When the second shackle end is inserted, after passing it through a pair of car-door staples, C, Figs. 2 and 3, or otherwise applying it as a fastening or sealing device in customary or appropriate ways, said burr b' precludes its insertion in the threading-hole h, save against the back of the preliminarily fastened end, and the exposure of the face of the shackle is thus in- 90 95 100

sured. The fastening-punch is now inserted through said burr b' , as indicated in Fig. 2, and a like burr, b^2 , is formed on said second shackle end within said aperture a^2 . The seal 5 as thus completed is represented by Figs. 3, 3 $\frac{1}{2}$, 3 $\frac{3}{4}$.

Instead of Babbitt metal in modifications of this invention, I may use type-metal or other hard and brittle metallic alloys which melt at 10 a low temperature, so as to be handled more or less nearly like lead, and instead of tin other hard sheet metals may be used without departing from the spirit of this invention.

Having thus described my said improvement 15 in seals, ("T,") I claim as my invention and desire to patent under this specification—

The within-described improved seal com-

posed of a flexible shackle of tin or like sheet metal and a hard and brittle seal-disk of Babbitt metal or the like, the latter constructed 20 with a threading-hole extending nearly but not quite through the seal-disk parallel to its sides, a pair of punching-apertures formed in and perpendicular to the respective sides of the disk, and a solid bottom to engage with and 25 mask the extremities of the shackle ends, retaining-burrs being formed on both shackle ends within the respective punching-apertures, so that both ends are uniformly and securely fastened, as herein set forth.

EDWARD J. BROOKS.
